(57) **CLAIM**

The ornamental design for a massage applicator, as shown and described.

DESCRIPTION

FIG. 1 is a front, left perspective view from above of a massage applicator, with its protective cap on, showing the new design;

FIG. 2 is a front, left perspective view from below of the massage applicator of FIG. 1;

FIG. 3 is a front elevation view of the massage applicator of FIG. 1;

FIG. 4 is a rear elevation view of the massage applicator of FIG. 1;

FIG. 5 is a left side elevation view of the massage applicator of FIG. 1;

FIG. 6 is a right side elevation view of the massage applicator of FIG. 1;

FIG. 7 is a top plan view of the massage applicator of FIG. 1;

FIG. 8 is a bottom plan view of the massage applicator of FIG. 1;

FIG. 9 is an exploded front, left perspective view from above of the massage applicator of FIG. 1;

FIG. 10 is an exploded front, left perspective view from below of the massage applicator of FIG. 1;

FIG. 11 is an exploded front elevation view of the massage applicator of FIG. 1;

FIG. 12 is an exploded rear elevation view of the massage applicator of FIG. 1;

FIG. 13 is an exploded left side elevation view of the massage applicator of FIG. 1;

FIG. 14 is an exploded right side elevation view of the massage applicator of FIG. 1;

FIG. 15 is a top plan view of the massage applicator of FIG. 1;

FIG. 16 is a bottom plan view of the massage applicator of FIG. 1;

FIG. 17 is a top plan view of the massage applicator of FIG. 1, taken with the protective cap removed for ease of illustration;

FIG. 18 is a bottom plan view of the massage applicator of FIG. 1, taken with the massage applicator removed for ease of illustration;

FIG. 19 is a front, left perspective view from above of the massage applicator of FIG. 1, with its protective cap removed;

FIG. 20 is a front, left perspective view from below of the massage applicator of FIG. 1, with its protective cap removed;

FIG. 21 is a front elevation view of the massage applicator of FIG. 1, with its protective cap removed;

FIG. 22 is a rear elevation view of the massage applicator of FIG. 1, with its protective cap removed;

(Continued)

FIG. 23 is a left side elevation view of the massage applicator of FIG. 1, with its protective cap removed; FIG. 24 is a right side elevation view of the massage applicator of FIG. 1, with its protective cap removed; FIG. 25 is a top plan view of the massage applicator of FIG. 1, with its protective cap removed; and, FIG. 26 is a bottom plan view of the massage applicator of FIG. 1, with its protective cap removed.

The portions shown in phantom (broken lines) are for illustrative purposes only and form no part of the claimed design.
